LOCOMOTIVE FRONT END CONSTRUCTION

Harry A. Hoke, Altoona, Pa., assignor to The Pennsylvania Railroad Company, Philadelphia, Pa., a corporation of Pennsylvania

Application June 4, 1936, Serial No. 83,410

8 Claims. (Cl. 213—4)

This invention relates to a front end construction for a locomotive or the like, and particularly to the form of the pilot and the manner in which the pilot coupler is mounted thereon.

It often occurs that when a locomotive strikes an automobile, or similar object at a grade crossing, the forwardly projecting front coupler of the locomotive either penetrates the side of the vehicle, or the vehicle is caught under the coupler and retained in that position until the speed of the locomotive is reduced. Thus the vehicle is carried for a distance and eventually dropped along the track, the locomotive passing over the wreckage, demolishing it, and usually fatally injuring the occupants.

One object of the present invention is to provide a front end construction for a locomotive or the like, characterized by a housing for the reception of the pilot coupler when such coupler is not in use, and further characterized by a pilot with deflecting surfaces so formed and so related to the housed coupler as to minimize the possibility of carrying or dragging an object struck by the locomotive. As a result of such novel construction, vehicles or other objects struck by the locomotive are caused to be immediately thrown off the track, lessening the damage to the vehicle and its occupants, and decreasing the possibility of derailment of any part of the passing train.

Another object of the invention is to provide, in a locomotive front end construction of the character described, a pilot and supporting means for the pilot coupler, all formed integrally with the bumper beam, and presenting substantially solid deflecting surfaces to objects along the track.

Another object of the invention is to provide novel means for limiting the swinging movement of the pilot coupler when in use, and for maintaining the pilot coupler when not in use in a housed position with the head of the coupler positioned substantially flush with the general configuration of the deflecting surfaces of the pilot.

Another object of my invention is to provide a locomotive front end construction of the character described, in which the bumping load is better diffused throughout the front end, reducing localized strains.

Other more specific objects and advantages characterizing my invention will become more fully apparent from the description hereinafter set forth of one embodiment or example thereof,

having reference to the accompanying drawings. Of the drawings:

Fig. I represents a plan view of a locomotive front end construction embodying my invention, and showing the pilot and coupler in its housed position.

Fig. II represents a side elevation of the same.

Fig. III represents a front elevation of the same.

Figs. IV, V and VI, represent vertical cross sections of the same, taken as indicated by the lines IV—IV, V—V and VI—VI, respectively, of Fig. III.

Fig. VII represents a perspective view of the front end construction, with the separate sections spaced apart to show details of construction.

Fig. VIII shows a perspective view of a locomotive front end construction for another form of my invention.

Fig. IX is a plan view showing the coupler in assembled relation with the front of Fig. VIII, only the pertinent portion of the front being shown, and that partially in section.

Fig. X is a sectional view, taken about the lines X—X of Fig. IX.

Fig. XI is an exploded view of the elements associated with the coupler in its assembled relation with the locomotive front, the coupler and front being omitted; and,

Fig. XII is a perspective view of a locking element.

With reference to the drawings, Figs. I—VII, there is shown a particular example of my invention in which a locomotive front end is built up of three separate sections rigidly secured together and each comprising an integral casting.

The central section includes the central portion 1 of a bumper beam, and a pilot 2 formed integrally with the bumper beam and projecting outwardly and downwardly therefrom. The front surfaces 3 of the pilot converge forwardly towards the center line of the locomotive, and form deflecting surfaces which tend to throw off to the side of the track any objects struck thereby. The pilot is cut away at one side as indicated at 4 to form a recess therein for housing the pilot coupler 5. Desirably an upstanding block 6 is formed at the opposite side of the pilot 2, the block having a side wall 7 which serves to limit swinging of the pilot coupler 5 towards that side of the pilot. From the central portion 1 of the bumper beam, there extends forwardly a projection 8, reinforced by webs 9, and

having a circular opening 10 which serves to accommodate one end of the coupler pin 11. At the coupler housing 4, there is formed a horizontal shelf 12. Above this shelf 12 there are 5 two circular ledges 13, 14, arranged in stepped formation. The upper ledge 14 has an opening 15 therein for supporting the lower end of the coupler pin 11, whereas the lower ledge 13 is formed substantially complementary to the 10 shoulders 16 at the bottom of the coupler 5, as shown most clearly in Fig. III. At the top of the block 6 there is provided an additional shelf 17. Desirably the pilot 2 is of substantially triangular cross section, as shown most clearly in 15 Fig. VII, and has openings 18 in its lower portion to render the same as light as possible, consistent with the desired strength, and the central portion 1 of the bumper beam is of cellular form, having a series of box-like divisions 19.

20 The wing sections of the locomotive front end construction include wing portions 1a, 1b of the bumper beam, and wing portions 2a, 2b of the pilot. As shown most clearly in Fig. VII, each wing section is of substantially triangular cross 25 section and includes a shelf 17a, 17b at the level of the shelf 17 of the central section. The front surfaces 3a, 3b of the wing sections are substantially solid, merging with and forming continuations of the deflecting surfaces 3 of the central section. Preferably, the surfaces 3a, 3b are rounded to provide smooth curves at each side of the locomotive. Steps 26 are formed in the surfaces 3a, 3b to enable a man to mount to the 30 top of the pilot. For the purpose of lightening the structure, holes 21 are provided interiorly of each wing section. The wing sections are rigidly secured to the central section by bolts passing through holes 22. The two wing sections are substantial counterparts of each other, except 35 that a side wall 23 is formed opposite the block 6 for defining one end of the coupler housing 4.

As shown in Fig. I, the central section 1 of the bumper beam is joined to the end sections 1a, 1b, with longitudinal frame members 24 of the locomotive interposed therebetween. In this manner the sections of the bumper beam are rigidly 40 united to the vehicle frame as well as to each other, and the bumping load is better diffused and distributed. Surrounding the base of the 45 three sections of the locomotive front end, there is a guard 25 in the form of a continuous skirt extending horizontally around the bottom edge of the pilot and secured thereto.

For limiting the swinging movement of the 50 coupler 5, a movable stop member 26 is employed. The stop member 26 is desirably attached to the locomotive as a permanent fixture by means of flexible chain 27, as shown in Fig. III, and it has thereon a pair of depending pins 28 which fit alternatively, either within a pair of holes 30, or within a pair of holes 31 in the lower ledge 13. When the coupler is in use, the stop member 26 is positioned with its pins 28 55 registering with the holes 31. Under this condition, angular movement of the coupler 5 is limited at the one side by the wall 7 of the block 6, and at the other side by the end of the stop member 26. When the coupler 5 is not used, it is housed by withdrawing the stop member 26, and swinging the coupler 5 inwardly into the housing 4 to the position shown in Figs. I and III, and then replacing the stop member 26 with its pins 28 engaging the holes 30. Under this condition the coupler 5 is held in fixed position within the housing 4. The coupler hous-

ing 4 is so designed that when the coupler 5 is swung inwardly, a wall 32 of the coupler is maintained substantially flush with the general configuration of the deflecting surfaces of the pilot. In other words, the wall 32 of the coupler 5 supplements the function of the block 6 at the other side of the pilot to reduce to a minimum the size of the opening at the front of the housing 4.

In Figs. VIII-XII there is shown another form 10 of my invention. The locomotive front shown in perspective in Fig. VIII is similar to the front described above in relation to Figs. I-VII. This second form of front is formed with a more regular and more inclined front surface, the 15 guard 25 and the shelves 17a, 17b of the first form of front being eliminated. Also the shelf 12 in the second form has been limited to the housing recess 4 and does not extend out in front of the pin 11 as in the first form. It is 20 also to be noted that wall 7 of the first form has been eliminated in the second form, leaving a rounded edge 41 to limit the movement of the coupler 5.

The coupler 5 in the second form of my invention has welded to its rear end a bumping block 45 and a ring 46 cut out to receive the shank of the coupler 5 to which the ring 46 is welded at its ends 47. The ring 46 is also welded at points 48 to the block 45 which is rounded 25 to conform to the inner surface of the ring 46. The coupler 5 is held in place by pin 11 as in the first form, the space behind the pin 11 being increased, and a concave bumping wall 49 provided 30 having the same curvature as the outer surface of ring 46 with which there is sliding contact. Two washers 54 are shown on top of the coupler 5 between it and the underside of projection 8. These washers 54 are used for making adjustments for wear of wheels, deflection of springs, etc., and sometimes one or both of them are placed under the coupler instead of both on top, as shown.

The coupler 5 is maintained either in its operating or in its housed position by means of 45 locking element 50 which fits into holes 51, 52 in ledge 13. In Fig. IX the coupler 5 is shown in its operating position with the locking element in hole 51. The broken lines show the coupler 5 in its housed position with locking element 50 50 in hole 52. In the housed position the coupler 5 is held snugly against the rear wall of the coupler housing 4. The locking element 50 is attached to the coupler 5 by chain 27. The coupler 5 is further supported on the ledge 13 55 by means of a bearing plate 55 which is cut out at 56 to allow locking element 50 to seat in holes 51 and 52. The bearing plate 55 is held in place by pins in the holes 58 which are in registry with holes 57 in shelf 13.

It will be seen that in this form of my invention the bumping load on the pin 11 is to a considerable extent reduced and taken by the bumping block 45 and wall 49 to be diffused through the entire front end of the locomotive. The 65 ring 46 closes to a large extent the opening in the locomotive front when the coupler 5 is in its housed position. This alone is a material reduction in the necessary irregularities in the front face on which objects might catch in cases of 70 collision.

From the above description it will be apparent that the locomotive front end of this invention is characterized by a pilot having substantially solid deflecting surfaces surrounding a coupler hous- 75

ing, there being no projections or sharp edges extending forwardly from such solid surfaces. Moreover, the pilot being formed integrally with the bumper beam is materially strengthened and rendered capable of withstanding a severe shock without distorting or damaging the front end of the locomotive. The bumping load is well diffused through the entire front and localized strains are reduced. The coupler may readily be swung from a forwardly extending position to a housed position, and when housed becomes itself a part of the pilot assisting in deflecting away from the track any object struck thereby.

While I have described my invention with reference to two specific examples thereof, and have disclosed herein a front end construction made up of several sections secured together, it will be apparent that various changes may be made in the form of the construction herein selected for illustration, and that the invention is not limited to a sectional type of front end, but comprehends many variations. Also, it will be apparent that certain features of the invention may at times be used to advantage without a corresponding use of other features, all without departing from the spirit of the invention as defined in the annexed claims.

Having thus described my invention, I claim:

1. In a front end for a locomotive or the like having frame members, a bumper having a central portion and separate wing portions, said frame members extending between said wing portions and said central portion and being attached thereto, a pilot formed integrally with the central portion of said bumper and having substantially solid converging deflecting surfaces, separate wings attached to said pilot and formed integrally with the separate wing portions of said bumper and extending forwardly at the sides of the pilot and presenting substantially smooth and solid front surfaces merging with and forming functional continuations of the deflecting surfaces of the pilot, a coupler housing formed in the upper part of said pilot between said wings, forwardly extending projections formed integrally with the central portion of said bumper and adapted to support the ends of a coupler pin, and a coupler pivotally mounted between said projections, said coupler being adapted when not in use to be received within said housing.
2. In a front end for a locomotive or the like, a bumper having separate ends, a pilot formed integrally with said bumper and having substantially solid converging deflecting surfaces, separate wings attached to said pilot and formed integrally with the ends of said bumper and extending forwardly to present substantially solid front surfaces merging with and forming lateral continuations of the deflecting surfaces of the pilot, a coupler housing formed in the upper portion of said pilot between said wings, and a coupler pivotally mounted on said bumper and adapted when not in use to be received within said housing.
3. In a front end for a locomotive or the like, a bumper, a pilot formed integrally on said bumper, a coupler having a bumping block at its back end, said bumping block having a ring attached thereto for increasing the bumping area, and a bumping wall formed in said integral bumper and pilot, said bumping wall being in sliding contact with the ring of said bumping

block for distributing the bumping load through said front end for a locomotive or the like.

4. In a front end for a locomotive or the like, a bumper, a pilot on said bumper, a coupler having a bumping block at its rear end, said coupler being in a recess in said pilot, a ring cut out to receive the coupler shank and attached thereto, said ring extending around said bumping block which is curved to fit said ring, and a concave bumping wall formed in said pilot, said wall being in sliding contact with said ring.

5. In a front end for a locomotive or the like, a bumper, a pilot on said bumper having substantially solid converging deflecting surfaces, wings extending forwardly from said bumper at the sides of the pilot, said wings having substantially solid front surfaces merging with and forming continuations of the deflecting surfaces of the pilot, a coupler housing disposed between said wings, a ledge near the base of said housing, a coupler having a bumping block pivotally mounted for swinging movement around said ledge, a locking element adapted to occupy different positions on said ledge to limit the swinging of the coupler, a ring cut out to receive the coupler shank and attached thereto, said ring extending around the bumping block, and a bumping wall in sliding contact with said ring, said coupler being adapted to be received within the housing and to be maintained therein by said locking element with the coupler head and said ring substantially flush with the general configuration of said deflecting surfaces.

6. In a front end for a locomotive or the like, a bumper, a pilot on said bumper having substantially solid converging deflecting surfaces, a coupler housing disposed within said deflecting surfaces, a coupler pivotally mounted in said housing and adapted when not in use to be received within the housing with the coupler head maintained substantially flush with the general configuration of said deflecting surfaces, and a ring extending around the back end of the coupler, said ring being of a size that its outer surface lies close to one edge of said coupler housing so that the surface of said ring is a general continuation of said deflecting surfaces.

7. The invention of claim 6 characterized further by the fact that the back end of said coupler is formed to fit the inner surface of said ring and said ring is in sliding contact with a concave bumping wall formed in said coupler housing.

8. In a front end for a locomotive or the like, a bumper, a pilot on said bumper having substantially solid converging deflecting surfaces, wings extending forwardly from said bumper at the sides of the pilot, said wings having substantially solid front surfaces merging with and forming continuations of the deflecting surfaces of the pilot, a coupler housing disposed between said wings, and a coupler pivotally mounted at said housing and adapted when not in use to be received within the housing with the coupler head maintained substantially flush with the general configuration of said deflecting surfaces, said coupler having a ring extending around the back part of the coupler, said ring being cut out to receive the coupler shank, whereby the coupler in its housed position offers a more uniform deflecting surface.
